[57] CLAIM

The ornamental design for a bottle, as shown and described.

DESCRIPTION

FIG. 1 is a perspective view of a bottle embodying our new design;

FIG. 2 is a top plan view thereof;

FIG. 3 is a bottom plan view thereof;

FIG. 4 is a side elevation thereof, the front, rear and opposite side of the claimed design are the same as the side shown in FIG. 4; and,

FIG. 5 is another side elevational view thereof representing a rotation of the bottle about its vertical center axis from the side elevational view depicted in FIG. 4.

The broken lines showing a bottle neck in FIGS. 1,2,4 and 5 are for illustrative purposes only and do not form part of the claimed design.
